UNITED STATES PATENT OFFICE.

ERNST RUHMER, OF BERLIN, GERMANY.

CONTRIVANCE FOR TRANSMITTING SOUND TO SOLID SOUND-CONDUCTORS.

1,174,613.

Specification of Letters Patent. Patented Mar. 7, 1916.

Application filed February 20, 1913, Serial No. 749,620. Renewed July 22, 1915. Serial No. 41,426.

To all whom it may concern:

Be it known that I, ERNST RUHMER, subject of the Emperor of Germany, residing at Friederichstrasse 248, Berlin, S. W., 48, 5 Germany, have invented a new and useful Improved Contrivance for Transmitting Sound to Solid Sound-Conductors, of which the following is a specification.

The present invention relates to a contrivance for transmitting sound and more especially speech vibrations, to solid sound conductors by means of a telephone or similar receiver, in which contrivance the variations of electric current corresponding to 15 the speech vibrations or to the electro-magnetic fluctuations generated thereby, are translated into mechanical vibrations.

The feature of the present invention resides in the employment of a resilient auxiliary element, which is itself set in mechanical vibration and is more or less fixed at one portion thereof but can freely vibrate elsewhere, for transmitting the electro-magnetic fluctuations or the vibrations of a fixed 25 vibrating element, viz: the telephone diaphragm, to the solid sound conductor. The transmission of the fluctuations of the magnetic field of the telephone and the vibrations of the diaphragm thereof, to this auxiliary conductor is effected at the last mentioned freely vibratory portion, where the vibrations are of greatest amplitude, either magnetically, mechanically or in some other manner, while the propagation of the vibrations 30 to the solid sound conductor occurs at or in the neighborhood of the node of the auxiliary vibratory element. In this manner, to a certain extent, a loose coupling is established between the telephone receiver 35 and the propagating element so that relatively little damping of the vibrations takes place, whereas with a direct coupling very considerable damping would occur, rendering any propagation of sound negligible.

45 The present contrivance is especially applicable for transmitting the sound effect of a telephone, influenced by a microphone current, to the bones of the human head, and thereby directly to the auditory nerves, 50 without necessarily traversing the external human organs of hearing, for the purpose of rendering a person, whose external organs of hearing are defective but whose auditory nerves are still intact, receptive of 55 sound waves.

In a constructional example of the inven-

tion illustrated in perspective on the accompanying drawing, the hearing apparatus consists of a clamp, comprising an interrupted ring *r*, which is contracted by a piece of rubber and is thereby pressed against the bones of the skull of the wearer thereof. A 60 resilient spring bar *f* is secured to this ring, the upper portion of which is connected by a thread or wire *d* to the center of the diaphragm *m* of a telephone receiver *t*, carried by the clamp. 65

On speaking into a microphone connected electrically to the telephone, a person wearing the contrivance hears the transmitted 70 sound waves, without the latter having to traverse the external organs of hearing. In this example the ring and the bones of the head constitute the solid sound conductor.

The hearing appliance described is intended to be a representative example of 75 the invention described broadly in the beginning of this specification.

I claim:

1. In a contrivance for transmitting 80 sound vibrations to solid sound conductors, a telephone receiver, a diaphragm of said telephone receiver, an elastic element secured at one portion thereof to the said solid sound conductor and a flexible link connecting said diaphragm to a freely vibratory 85 portion of said elastic element.

2. In a contrivance for transmitting sound to the bones of the human head, a clamp in close contact with the head, an elastic spring secured at one portion thereof 90 to said clamp, a telephone receiver carried on said clamp, a diaphragm of said telephone receiver and a link connecting said diaphragm to a freely vibratory part of 95 said elastic spring.

3. In a device for transmitting sound vibrations to solid sound conductors, a vibrating diaphragm, an elastic element, a loose coupling between said elastic element 10 and said vibrating diaphragm, a solid sound conductor, and a close coupling between said elastic element and said solid sound conductor.

4. In an apparatus for transmitting sound vibrations to solid conductors, a vibratory diaphragm, a solid sound conductor, an elastic element which can vibrate with a loop at one end and a node at the other end, a connection between said diaphragm and the loop end of said elastic element, and a connection between said solid sound 110 con-

ductor and the nodal end of said elastic element.

5. In a device for transmitting sound vibrations to solid sound conductors, a vibratory diaphragm, a solid sound conductor, an elastic element attached at one end to said solid sound conductor, and a flexible connection between said diaphragm and the free end of said elastic member, said flexible connection being normally held under tension.

10. In a contrivance for transmitting sound vibrations to solid sound conductors, a vibratory diaphragm, a solid sound conductor, a flexible connecting member at-

tached at one end to said diaphragm, and an elastic member secured to the other end of said flexible connecting member, whereby both of said members are normally held under tension, said elastic member being 20 also connected with said solid sound conductor.

In testimony whereof I have signed my name to this specification in the presence of two subscribing witnesses.

ERNST RUHMER.
